ISOMERIZATION OF LIGHT HYDROCARBONS

Filed April 30, 1943

UNITED STATES PATENT OFFICE

2,504,280

ISOMERIZATION OF LIGHT HYDROCARBONS

Bernard H. Shoemaker, Hammond, Ind., and Bernard L. Evering, Chicago, Ill., assignors to Standard Oil Company, Chicago, Ill., a corporation of Indiana.

Application April 30, 1943, Serial No. 485,156

21 Claims. (Cl. 260—683.5)

1

This invention relates to the isomerization of pentane or other light saturated hydrocarbons in the butane to heptane boiling range by means of hydrogen fluoride catalyst compositions and it pertains more particularly to improved methods and means in such processes for avoiding undesirable side reactions, e. g., for suppressing cracking, disproportionation, etc.

Pentane as well as lighter and heavier paraffins, undergo reactions in the presence of substantial amounts of hydrogen fluoride catalysts to produce a variety of products, chiefly paraffinic hydrocarbons of branched-chain structure. Heretofore such conversions have resulted in considerable amounts of cracking, disproportionation or other side reactions so that the conversion of a narrow boiling range charging stock has resulted in a relatively wide boiling range product. One example of the disproportionation reaction is: $2C_5H_{12} \rightarrow C_4H_{10} + C_6H_{14}$. An object of our invention is to direct the hydrocarbon conversions primarily toward isomerization and to avoid such side reactions as the cracking of charging stock to low molecular weight hydrocarbons or the conversion of charging stock into higher molecular weight hydrocarbons. A further object is to prolong catalyst activity and catalyst life or, in other words, to produce a larger yield of desirable isomerization products per pound of catalyst material than has heretofore been possible. Another object is to provide an improved system for isomerizing hydrocarbons with hydrogen fluoride. Other objects will be apparent as the detailed description of the invention proceeds.

In practicing our invention we may for example isomerize normal pentane to isopentane by contacting normal pentane with approximately an equal amount of hydrogen fluoride at a temperature of about 350 to 400° F. and a pressure of about 1500 to 2500 pounds per square inch with intimate contacting in the presence of a small amount of a cracking inhibitor. A preferred example of such cracking inhibitor is a cyclic hydrocarbon such as an aromatic or naphthenic hydrocarbon. Generally aromatics are employed in amounts of about .05 to 3% by volume based on pentane charged. Naphthenes should be employed in larger quantities, i. e., within the approximate range of .5 to 15% by volume based on charge; in other words about .5 to 15% by volume of naphthenes is the equivalent of .05 to 3% by volume of aromatics, a unit volume of aromatics being equivalent to about 5 to 10 unit volumes of naphthenes as cracking inhibitors in our process. The isomerization may also be

2

effected under hydrogen pressure. The invention is not limited to pentane nor to these particular conditions but will be more fully understood as the following detailed description proceeds.

The accompanying drawing which forms a part of this specification is a schematic flow diagram of a commercial plant for isomerizing pentane with hydrogen fluoride in the presence of a small amount of a cyclic hydrocarbon cracking inhibitor.

The charging stock for our process is preferably a saturated C_5 hydrocarbon rich in normal pentane although a saturated light naphtha may be employed if it is substantially free from olefins. Generally speaking, we may use any saturated hydrocarbons from butane to heptane in boiling range and any mixtures thereof, a fraction from natural gas being highly advantageous. Hydrocarbons synthetically produced by carbon monoxide-hydrogen synthesis or the hydrogenation of carbonaceous materials are likewise highly advantageous provided they are suitably treated for the saturation of olefins or the removal thereof. Virgin light naphtha fractions having end points up to 150° F. or 200° F. are available in most refineries and may be used per se as our charging stock or may be further fractionated and one or more fractions thereof employed as charging stock.

The catalyst employed in our process is either hydrogen fluoride per se or a hydrogen fluoride composition. Hydrogen fluoride is only slightly miscible with hydrocarbons at room temperature, has a boiling point of about 67° F., a melting point of -117° F., a critical temperature of about 446° F., and a specific gravity of about 1.0 at 32° F. so that it may be readily separated from hydrocarbons by distillation, stratification and other commercial separation means. At low temperatures hydrogen fluoride tends to polymerize and its formula may range from $(HF)_6$ at low temperatures to HF at high temperatures. The average molecular weight of hydrogen fluoride is also dependent on pressure. The miscibility of hydrogen fluoride with hydrocarbons and the density of liquid hydrogen fluoride will thus vary considerably with differences in temperature and pressure. An outstanding advantage of hydrogen fluoride over catalysts of the aluminum chloride type is the ease of recovery from reaction mixtures. Along with hydrogen fluoride per se we may employ other catalyst components such as fluorides of boron, aluminum, zinc, antimony, iron, nickel, cobalt, zirconium, etc.

Generally speaking, the weight ratio of hydrogen fluoride catalyst to charging stock in the reaction zone may range from about 0.25:1 to 5:1 and it is preferably in the approximate range of 1:1 to 2:1 or more. The conversion temperature is usually within the approximate range of 150° F. to 500° F. or higher and, for example, may be about 300° F. to 400° F. Higher temperatures may be employed with decreased contact times and vice versa. The weight space velocity in the reaction zone may vary through a considerable range but it is preferably in the approximate range of about .05 to 5, e. g., about .5 pound of charging stock per hour per pound of catalyst in the conversion zone. The pressure in the conversion zone is preferably sufficient to maintain liquid or at least dense phase conversion conditions and may be within the approximate range of about 100 to 3000 pounds per square inch.

In order to direct the conversion of pentane or other C₄ to C₇ saturated hydrocarbons toward true isomerization and to avoid unduly large

pressure may be still more essential and it should be of the order of 500 to 3000 pounds per square inch. When optimum hydrogen pressures are employed in the conversion it is not so essential that the charging stock contain the critically defined percentages of aromatics or naphthenes but for best results, particularly in the case of heptanes and hexanes, we employ both the critically defined amounts of aromatics or naphthenes and the stated hydrogen partial pressures.

Our invention is strikingly demonstrated by the following series of experimental runs made on normal pentane with hydrogen fluoride as the catalyst in the absence of added hydrogen and both with and without benzol as an inhibitor for undesired side reactions. In these runs a bomb was employed as the reactor, and it was provided with means for securing the required amount of agitation on intimate mixing. The amounts of catalyst and inhibitor used, the conversion conditions, and the results obtained are set forth in the following table:

	A	B	C	D	E	F	G
Materials:							
Parts n-pentane (by vol.)	100	100	100	100	100	100	100
Parts HF (by volume)	21.5	21.5	100	100	100	100	26
Parts HF (by weight)	34	34	158	158	158	158	41
Parts benzol (per cent by vol.)					0.2	1.0	0.7
Conditions:							
Temperature (°F.)	330	375	375	330	330	400	400
Pressure (p. s. i.)	980	1,850	2,600	1,100	1,100	2,200	2,100
Time (hours)	6	3	3	3	3	3	3
Products:							
C ₄ hydrocarbons (wt. per cent)		1	29	23	3.5	-----	-----
Isopentane (wt. per cent)		5	24	28	16.0	30	-----
Normal pentane (wt. per cent)	100	94	20	29	77.0	70	100
C ₆ and heavier (wt. per cent)			27	20	3.5	-----	-----

amounts of disproportionation, cracking and other side reactions we employ with a paraffinic charging stock an amount of aromatics in the approximate range of 0.05 to 3% or naphthenes within the approximate range of .5 to 15%. Hexanes require more added cyclic hydrocarbons than pentane and pentane requires more than butane; as much as 5% benzol may be required for hexane while as little as 0.01% may be sufficient for butane. In general, in isomerizing paraffinic hydrocarbons such as those boiling in the butane to heptane boiling range, we may use an amount of aromatic hydrocarbon ranging from about 0.05 to about 5 percent by weight. When both aromatics and naphthenes are used the amounts of each may be correspondingly reduced, one part of aromatic being equivalent to 5 or 10 parts of naphthenes.

In the case of pentane, hexanes or heptanes, we may effect the conversion in the presence of added hydrogen. The necessary amount and partial pressure of the added hydrogen is likewise dependent upon the particular charging stock. With butanes and pentanes the hydrogen may be entirely dispensed with provided that the proportion of aromatics or naphthenes in the charging stock is within the critical range hereinabove set forth. With a pentane charge somewhat improved results may be obtained by relatively low hydrogen partial pressures, i. e., partial pressures of the order of 50 to 500 pounds per square inch at conversion temperatures of the order of 150° F. to 400° F. With hexanes the addition of hydrogen may be more essential and the hydrogen partial pressure should be within the approximate range of 250 to 1000 pounds per square inch. With heptane the hydrogen partial

Run A shows that no conversion is obtained with as little as about one-third part by weight or one-fifth part by volume (based on charge) of hydrogen fluoride at 330° F. Run B shows that when the temperature is increased to 375° F. with the consequent increase in pressure for maintaining liquid or at least dense phase conditions, a small amount of conversion is obtained, but there is about one part by weight of C₄ hydrocarbons formed for five parts by weight of isopentane. Run C shows that at 375° F. a substantial amount of conversion is obtained when the amount of catalyst is increased to about 1.5 parts by weight or equal parts by volume based on charge; this run also shows that the conversion is chiefly disproportionation, the amount of lighter and heavier conversion products far exceeding the amount of isopentane produced. Run D shows that disproportionation is likewise obtained at 330° F. when approximately 1.5 parts by weight of hydrogen fluoride is employed as compared with the one-third part by weight in Run A.

Run E is substantially identical with Run D except that about .2 part by volume of benzol is added to pentane charging stock. This small amount of added benzol is shown to have the remarkable and unexpected effect of inhibiting cracking and disproportionation. The butane production dropped from 23 to 3.5% by weight and the amount of C₆ and heavier hydrocarbons likewise dropped from about 20% to 3.5%. Without the small amount of aromatic inhibitor (i. e., in Run D), the disproportionation products, C₄ hydrocarbons+C₆ and heavier, amounted to almost twice the total isopentane production. In the presence of only 0.2% of benzene, the amount of isomerization product, isopentane,

was more than twice the combined amounts of C₄ hydrocarbons and C₆ and heavier hydrocarbons.

Run F was at a temperature of 400° F. and with 1.0% by volume of added benzene in the pentane charge. The higher conversion temperature would naturally lead to more cracking and disproportionation but the larger amount of aromatics was found to practically inhibit cracking and disproportionation so that the conversion product was substantially wholly isopentane, about 70% of the charge remaining unreacted. By separating isopentane from unreacted normal pentane and retreating the latter in multi-stage or continuous processes, it should thus be possible to convert normal pentane almost quantitatively into isopentane.

Run G brings out quite strikingly the fact that when hydrogen fluoride per se is employed as the catalyst, the concentration thereof in the reaction zone should be substantial. Run G, like Run F, was at 400° F. and in Run G about 0.7 part by volume of benzol was employed for inhibiting cracking and disproportionation. Since a small amount of conversion was obtained in Run B, with a somewhat smaller amount of catalyst and a somewhat lower temperature, it would naturally be expected that at least an equal amount of conversion would be effected at 400° F. The 0.7 per cent by volume of benzol in Run G evidently inhibited not only the cracking and disproportionation, but likewise inhibited isomerization itself since in this run there was no appreciable conversion. The failure to obtain any conversion in Run G was apparently due to the fact that the concentration of hydrogen fluoride was too low.

The above runs clearly bring out the fact that with hydrogen fluoride as a catalyst, there must be a substantial amount of catalyst present to effect any conversion. At least about 1 to 2 parts by weight of hydrogen fluoride should be present in the reaction zone for each part by weight of pentane charging stock if worth while conversions are to be obtained. Even small amounts of benzene inhibit cracking and disproportionation to a marked extent, but amounts upwards of about 3% may retard the desired isomerization reaction itself. We therefore employ aromatics within the approximate range of about 0.05 to 3, preferably about 0.1 to 1.0%. Excellent conversions are obtained at temperatures of the order of 350 to 400° F., but lower or higher temperatures may, of course, be employed.

While the above runs were made in batch reactors, it should be understood that we contemplate the use of continuous reactors either of the agitator type, the circulator-mixer type, or the tower type. Likewise, while the above runs were made on normal pentane, our invention is also applicable to the conversion of normal butane to isobutane, normal hexane and methyl pentanes to dimethyl butanes, etc.

An example of a commercial application of our invention for the isomerization of normal pentane is illustrated in the drawing and from the following detailed description thereof. A pentane charging stock containing both normal and isopentane is introduced through line 48 to isopentane tower 49 which may be operated at a pressure of about 25 pounds gauge with a top temperature of about 140° F. and a bottom temperature of about 160° F., the bottom temperature being obtained by the use of a suitable re-

boiler or reheater diagrammatically illustrated by coil 12. Isopentane and lighter components are taken overhead. Normal pentane and heavier components are withdrawn through line 13 and introduced by pump 14 to rerun tower 15 which may be operated at about 25 pounds gauge pressure with a top temperature of about 159° F. and a bottom temperature of about 205° F., suitable reboiler being employed as diagrammatically illustrated by coil 16. Products heavier than normal pentane are withdrawn through line 17.

Normal pentane is taken overhead through line 18 and cooler 19 to receiver 20 from which a part of the accumulated liquid is returned through line 21 to serve as reflux in the rerun tower and another part is pumped by pump 22 through line 23 in heater 24 to isomerization reactor 25. About 1/2 barrel of benzene is introduced into line 23 from source 26 by pump 27 for each 100 barrels of pentane which is charged to the reactor.

The reactor itself may be of various types depending somewhat upon the conditions under which it is operated. It may, for example, be a reactor of the type employed for sulfuric acid alkylation as exemplified by the contactor described in U. S. Patent 2,233,802. A circulator or agitator in the reactor may be driven by motor 28. Under some conditions of operation a simple tower type reactor may be employed and the hydrocarbons may pass upwardly or downwardly depending on relative density through a column of liquid hydrogen fluoride. In this particular example, however, a mechanical agitator or circulator is employed so that relative densities of liquid hydrogen fluoride and hydrocarbons are of no particular consequence. In this example the reactor may be maintained at a temperature of about 400° F. and a pressure of about 2200 pounds per square inch. The actual time of contact of the pentane in the tower may be of the order of about 1 to 3 hours. The tower may contain about 1 to 2 volumes of hydrogen fluoride for each volume of hydrocarbon.

The product stream may be continuously removed through lines 29 and 30 to a high temperature separator 31. Separated hydrogen fluoride may be returned to the reactor through line 32 and the remaining product stream may be passed through line 33, line 34, cooler 35 and valve 36 to settling chamber 37 which may be at substantially atmospheric temperature, i. e., about 100° F. or lower and either at substantially conversion pressure or at somewhat reduced pressure. At the low temperature the bulk of the hydrogen fluoride separates out as a liquid and is returned through line 38 by pump 39 to reactor 25. The remaining product stream then passes through line 40 and pressure reducing valve 41 to azeotropic distillation still 42 which acts as a hydrogen fluoride stripper. This still may be provided with a suitable heating or reboiler means 43 at its base and it may be operated at pressures of the order of 25 to 250 pounds per square inch. This tower or still 42 is so operated that azeotropes are formed with low boiling hydrocarbons such as butane and these azeotropes are taken overhead through line 44 and cooler 45 to separator 46 which may operate at about atmospheric temperature, i. e., at temperatures readily obtainable by available condenser water. The condensed liquid separates into a heavy hydrofluoric acid layer which is withdrawn through line 47 and returned by pump

48 to reactor 25. The upper hydrocarbon layer flows over weir 49 and is returned through line 50 by pump 51 to the top of the azeotropic still 42. Any methane or other uncondensed gases may be vented from the top of the settler or reflux accumulator 46 either continuously or from time to time through line 52.

The liquid product together with butanes in excess of those required for azeotropic formation are withdrawn from the base of azeotropic still 42 through line 53 and are contacted in treating system 54 with bauxite at elevated temperatures or with other known contacting or treating agent for removing alkyl fluorides and preventing any hydrogen fluoride from reaching or being formed in the product fractionation system. The product thus freed from hydrogen fluoride and alkyl fluorides is returned from treating system 54 by line 55 to a point in isopentane tower 11 which is preferably above the point of charging stock inlet 10.

Any unisomerized pentane and higher boiling hydrocarbons pass downwardly in tower 11 and thence to rerun tower 15 from the top of which the isomerization charge is obtained. Any small amount of higher boiling hydrocarbons which may be formed during the isomerization is withdrawn through line 17.

The overhead from tower 11 will contain the isopentane from the original charge together with isopentane from the product stream and any small amount of butanes that may be present in the original charge or in the product stream. The overhead from tower 11 passes through line 56 and condenser 57 to accumulator 58. A part of the accumulated liquid is returned by pump 59 and line 60 for reflux in the top of tower 11. The remainder of the liquid from the accumulator is introduced by pump 61 and line 62 to debutanizer tower 63 which may operate at a pressure of about 100 pounds gauge with a top temperature of about 143° F. and a bottom temperature of about 224° F., a suitable reboiler being employed as diagrammatically illustrated by coils 64. The isopentane product stream is removed from the base of the debutanizer tower through line 65.

Hydrocarbons lighter than isopentane are taken overhead from the top of tower 63 through line 66 and cooler 67 to accumulator 68. If necessary or desirable, gases may be vented from the top of this accumulator through line 69. The accumulated liquid is removed by pump 70, a part being returned by line 71 to serve as reflux in the top of tower 63 and the remainder being withdrawn as a butane stream through line 72.

Makeup hydrogen fluoride may be introduced directly into the reactor through line 73 but is preferably introduced to the inlet of pump 48 through line 73a.

When a tower type of reactor is employed or where there is not a large carryover of hydrogen fluoride with the product leaving reactor 25 through line 29, the high temperature separator 31 may be dispensed with and the product stream may be simply by-passed through line 74. Various other modifications and alternative arrangements of the system may be apparent from the above description to those skilled in the art. Those skilled in the art will, of course, recognize the precautions that should be taken in handling hydrogen fluoride and with the proper precautions this reagent may be employed without undue hazards to the operators. In order to avoid corrosion difficulties the charging stock should,

of course, be substantially anhydrous and provision should be made throughout the system for preventing the entrance of any moisture. No invention is claimed in any of these expedients per se and no detailed description thereof appears to be necessary.

As a further example of our process we may isomerize normal hexane or methyl pentane for the production of dimethyl butane by first preparing a charging stock rich in normal hexane or methyl pentane and containing about 1 to 5% of aromatics or about .5 to 25% of naphthenes or both. This charging stock may then be intimately admixed with about 25 to 500% or more by weight, e. g. 150% by weight of hydrogen fluoride and contacted in a reaction zone at a weight space velocity of about .05 to 5, e. g., .5 pound of charging stock per hour per pound of catalyst in the reactor. The temperature of the reactor may be within the approximate range of about 250 to 500° F., e. g. about 400° F. The total reaction pressure may be of the order of 1000 to 4000 pounds per square inch, e. g. about 2500 pounds per square inch and the hydrogen partial pressure may be of the order of 250 to 1000, e. g., about 500 pounds per square inch. Here again both the use of the hydrogen pressure and the use of the critically defined amounts of aromatics or naphthenes tends to direct the conversion toward isomerization and to suppress undesirable cracking and disproportionation. The conjoint use of both inhibitors should give optimum results.

Examples of aromatic inhibitors which may be employed in the practice of our invention include benzene, toluene, xylenes, other alkyl benzenes, naphthalenes, etc. Examples of naphthenes include: cyclopentane, methyl cyclopentanes, cyclohexane, methyl cyclohexane, dimethyl cyclohexane, etc. We prefer as cracking inhibitors aromatics and naphthenes containing six carbon atoms although others may be used with good results.

While we have described in detail specific examples of our invention it should be understood that the invention is not limited to such examples nor to the conditions defined in connection therewith since modifications and alternate operations and operating conditions will be apparent from the above description to those skilled in the art.

We claim:

1. The isomerization process which comprises contacting a charging stock consisting essentially of liquid normal pentane with a catalyst consisting essentially of liquid, substantially anhydrous hydrogen fluoride in a conversion zone at a temperature between about 300 and about 400° F. under a pressure sufficient to maintain substantially liquid phase conversion conditions, maintaining an amount by weight of hydrogen fluoride in the conversion zone which is at least equal to the amount by weight of normal pentane therein, and effecting the conversion in said zone in the presence of between about 0.05 and about 3% by volume of an admixed aromatic hydrocarbon based on the normal pentane.

2. The process of claim 1 wherein the admixed aromatic hydrocarbon is benzene.

3. The method of isomerizing a normally liquid paraffinic hydrocarbon boiling within the boiling range of gasoline which comprises contacting said hydrocarbon in the liquid phase with at least an equal weight of a catalyst consisting essentially of liquid, substantially anhydrous hydrogen fluo-

ride at a temperature between about 150° F. and about 500° F. under a pressure sufficient to maintain the materials being contacted in the liquid phase, said pressure being between about 100 and about 3000 p. s. i., for a period of time sufficient to effect substantial isomerization of said paraffinic hydrocarbon, said contacting being effected in the presence of an admixed aromatic hydrocarbon in an amount between about 0.05 per cent and about 3 per cent by volume based on said paraffinic hydrocarbon.

4. The process of claim 3 wherein the admixed aromatic hydrocarbon is benzene.

5. The method of isomerizing hexanes which comprises contacting the same with at least an equal weight of liquid, substantially anhydrous hydrogen fluoride in the presence of between about 0.05 and about 3 per cent by volume of an admixed aromatic hydrocarbon, based on hexanes, at a temperature between about 150° F. and about 500° F. under a pressure sufficient to maintain the materials being contacted in the liquid phase, said pressure being between about 100 and about 3000 p. s. i., said contacting being effected in the presence of hydrogen in an amount sufficient to produce a hydrogen partial pressure between about 250 and about 1000 p. s. i.

6. The method of isomerizing heptanes which comprises contacting the same with at least an equal weight of liquid, substantially anhydrous hydrogen fluoride in the presence of between about 0.05 and about 3 per cent by volume of an admixed aromatic hydrocarbon, based on heptanes, at a temperature between about 150° F. and about 500° F. under a pressure sufficient to maintain the materials being contacted in the liquid phase, said pressure being between about 100 and about 3000 p. s. i., said contacting being effected in the presence of hydrogen in an amount sufficient to produce a hydrogen partial pressure between about 500 and about 3000 p. s. i.

7. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon a low boiling aromatic hydrocarbon in a small proportion sufficient substantially to inhibit said cracking conversion but insufficient substantially to inhibit said isomerization reaction, contacting the resultant mixture under isomerization reaction conditions with at least about an equal weight of a catalyst consisting essentially of liquid, substantially anhydrous hydrogen fluoride, and recovering from the effluents of said isomerization reaction a hydrocarbon fraction containing an isomeric paraffin so produced.

8. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon a low boiling aromatic hydrocarbon in an amount within the range of about 0.05 to about 5 percent by weight of the total hydrocarbons, contacting the resultant mixture under isomerization reaction conditions with at least about an equal weight of a catalyst consisting essentially of liquid, substantially anhydrous hydrogen fluoride, and recovering from the effluents of said isomerization

reaction a hydrocarbon fraction containing an isomeric paraffin so produced.

9. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon an aromatic hydrocarbon in a small proportion sufficient substantially to inhibit said cracking conversion but insufficient substantially to inhibit said isomerization reaction, contacting the resultant mixture under isomerization reaction conditions with at least about an equal weight of a catalyst consisting essentially of liquid, substantially anhydrous hydrogen fluoride, and recovering from the effluents of said isomerization reaction a hydrocarbon fraction containing an isomeric paraffin so produced.

10. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon selected from the group consisting of aromatic hydrocarbons and naphthenic hydrocarbons in a small proportion sufficient substantially to inhibit said cracking conversion but insufficient substantially to inhibit said isomerization reaction, contacting the resultant mixture under isomerization reaction conditions with at least about an equal weight of a catalyst consisting essentially of liquid, substantially anhydrous hydrogen fluoride, and recovering from the effluents of said isomerization reaction a hydrocarbon fraction containing an isomeric paraffin so produced.

11. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon a low boiling cyclic hydrocarbon selected from the group consisting of aromatic hydrocarbons and naphthenic hydrocarbons in a small proportion sufficient substantially to inhibit said cracking conversion but insufficient substantially to inhibit said isomerization reaction, contacting the resultant mixture under isomerization reaction conditions with at least about an equal weight of a catalyst consisting essentially of liquid, substantially anhydrous hydrogen fluoride, and recovering from the effluents of said isomerization reaction a hydrocarbon fraction containing an isomeric paraffin so produced.

12. A process for effecting the isomerization of an isomerizable normally liquid paraffin hydrocarbon boiling within the boiling range of gasoline while inhibiting cracking conversion which forms paraffin hydrocarbons of lower and higher molecular weights, which comprises admixing with said paraffin hydrocarbon a cyclic hydrocarbon selected from the group consisting of aromatic hydrocarbons and naphthenic hydrocarbons in a small proportion sufficient substantially to inhibit said cracking conversion but insufficient substantially to inhibit said isomerization reaction, contacting the resultant mixture with at least about an equal weight of a catalyst consisting essentially of liquid, substantially

11

anhydrous hydrogen fluoride at a temperature between about 150° F. and about 500° F. under a pressure sufficient to maintain the materials being contacted in the liquid phase, for a period of time sufficient to effect substantial isomerization of said paraffin hydrocarbon, and recovering from the effluents of said isomerization reaction a hydrocarbon fraction containing an isomeric paraffin so produced.

13. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon a low boiling cyclic hydrocarbon selected from the group consisting of aromatic hydrocarbons and naphthenic hydrocarbons in a small proportion sufficient substantially to inhibit said cracking conversion but insufficient substantially to inhibit said isomerization reaction, contacting the resultant mixture with at least about an equal weight of a catalyst consisting essentially of liquid, substantially anhydrous hydrogen fluoride at a temperature between about 300° F. and about 400° F. under a pressure sufficient to maintain the materials being contacted in the liquid phase, for a period of time sufficient to effect substantial isomerization of said paraffin hydrocarbon, and recovering from the effluents of said isomerization reaction a hydrocarbon fraction containing an isomeric paraffin so produced.

14. The process of claim 7 wherein the aromatic hydrocarbon is benzene.

15. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon a naphthenic hydrocarbon in a small proportion sufficient substantially to inhibit said cracking conversion but insufficient substantially to inhibit said isomerization reaction, contacting the resultant mixture under isomerization reaction conditions with at least about an equal weight of a catalyst consisting essentially of liquid, substantially anhydrous hydrogen fluoride, and recovering from the effluents of said isomerization reaction a hydrocarbon fraction containing an isomeric paraffin so produced.

16. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing with said paraffin hydrocarbon a low boiling naphthenic hydrocarbon in a small proportion sufficient substantially to inhibit said cracking conversion but insufficient substantially to inhibit said isomerization reaction, contacting the resultant mixture under isomerization reaction conditions with at least about an equal weight of a catalyst consisting essentially of liquid, substantially anhydrous hydrogen fluoride, and recovering from the effluents of said isomerization reaction a hydrocarbon fraction containing an isomeric paraffin so produced.

17. A process for effecting the isomerization of an isomerizable normally liquid paraffin hydrocarbon boiling within the boiling range of gasoline while inhibiting cracking conversion which

12

forms paraffin hydrocarbons of lower and higher molecular weights, which process comprises admixing with said paraffin hydrocarbon a low boiling naphthenic hydrocarbon in a small proportion sufficient substantially to inhibit said cracking conversion but insufficient substantially to inhibit said isomerization reaction, contacting resultant mixture with at least about an equal weight of a catalyst consisting essentially of liquid, substantially anhydrous hydrogen fluoride at a temperature between about 300° F. and about 400° F. under a pressure sufficient to maintain the materials being contacted in the liquid phase, for a period of time sufficient to effect substantial isomerization of said paraffin hydrocarbon, and recovering from the effluents of said isomerization reaction a hydrocarbon fraction containing an isomeric paraffin so produced.

18. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing cyclohexane with said paraffin hydrocarbon in a small proportion sufficient substantially to inhibit said cracking conversion but insufficient substantially to inhibit said isomerization reaction, said proportion being between about 0.5 and about 15% by volume, based on said paraffin hydrocarbon, contacting the resultant mixture with at least about an equal weight of a catalyst consisting essentially of liquid, substantially anhydrous hydrogen fluoride at a temperature between about 150° F. and about 500° F. under a pressure sufficient to maintain the materials being contacted in the liquid phase, for a period of time sufficient to effect substantial isomerization of said paraffin hydrocarbon, and recovering from the effluents of said isomerization reaction a hydrocarbon fraction containing an isomeric paraffin so produced.

19. A process for effecting the isomerization of an isomerizable normally liquid paraffin hydrocarbon boiling within the boiling range of gasoline while inhibiting cracking conversion which forms paraffin hydrocarbons of lower and higher molecular weights, which process comprises admixing a low boiling naphthenic hydrocarbon with said paraffin hydrocarbon in a small proportion sufficient substantially to inhibit said cracking conversion but insufficient substantially to inhibit said isomerization reaction, said proportion being between about 0.5 and about 15% by volume, based on said paraffin hydrocarbon, contacting the resultant mixture with at least about an equal weight of a catalyst consisting essentially of liquid, substantially anhydrous hydrogen fluoride at a temperature between about 150° F. and about 500° F. under a pressure sufficient to maintain the materials being contacted in the liquid phase, for a period of time sufficient to effect substantial isomerization of said paraffin hydrocarbon, and recovering from the effluents of said isomerization reaction a hydrocarbon fraction containing an isomeric paraffin so produced.

20. The process of claim 19 wherein the isomerization reaction temperature is between about 300° F. and about 400° F.

21. A process for effecting the isomerization of normal pentane while inhibiting cracking conversion which forms paraffin hydrocarbons of lower and higher molecular weights, which process comprises admixing cyclohexane with said nor-

mal pentane in a small proportion sufficient substantially to inhibit said cracking conversion but insufficient substantially to inhibit said isomerization reaction, said proportion being between about 0.5 and about 15 percent by volume, based on said normal pentane, contacting the resultant mixture with at least about an equal weight of a catalyst consisting essentially of liquid substantially anhydrous hydrogen fluoride at a temperature between about 350° F. and about 400° F. under a pressure sufficient to maintain the materials being contacted in the liquid phase, for a period of time sufficient to effect substantial isomerization of said normal pentane, and recovering from the effluents of said isomerization reaction a hydrocarbon fraction containing isopentane.
